UNITED STATES PATENT OFFICE.

ALBERT M. GUILLET, OF CHARLOTTE, NORTH CAROLINA.

SUPPORTING DEVICE FOR WELDING FLYERS.

Application filed November 11, 1927. Serial No. 232,623.

My invention relates to an adjustable supporting device for welding flyers, used in the manufacture of the textile fabrics which provides means for holding the flyer while the 5 same is being welded.

It is a matter well known in the art that one of the legs of the flyer is hollow, and through this hollow leg a thread is passed and a presser is rotatably mounted on the 10 outside of the hollow leg of the flyer, and due to the fact that the bearing surface of the flyer is located at the end of the hollow tube, this hollow tube of the flyer wears away and renders the flyer unfit for use until the same 15 is repaired by welding the worn end, thus filling up the worn away surface, after which this welded portion is ground to form and a new bearing surface is thus obtained for the presser.

20 Heretofore it has been the custom in building up these worn ends of the flyer by welding for one person to hold the flyer and turn the same while another person would do the welding.

25 Another object of my invention is to provide means for holding and turning a flyer while the same is being welded, said means being operated by application of the welder's foot thus dispensing with the service of an other person.

30 Some of the objects of my invention having been stated, other objects will appear as the description proceeds when taken in connection with the accompanying drawings, in which—

35 Figure 1 is a plan view of my holding device;

40 Figure 2 is a front elevation of my supporting device, showing a flyer in position ready to be welded;

45 Figure 3 is an elevation of the left hand end of Figure 2;

Figure 4 is an elevation of the right hand end of Figure 2;

50 Figure 5 is an enlarged detailed side elevation partly in cross section of the holding means for the flyer;

Figure 6 is a side elevation for the turning means for the flyer;

55 Figure 7 is a side elevation of Figure 6;

Figure 8 is an enlarged detailed view of

the tube leg of the flyer, showing the end portion thereof worn away and ready for welding.

Referring more particularly to the drawings, the numeral 10 indicates a table having the leg 11, and on top of this table and extending along the forward edge thereof is the metallic strip 12 which has at one end thereof the upstanding projections 13 and 14, in which projections the pin 15 is secured and rotatably mounted on this pin 15 is the wheel or cooperating holding device 16 which has the portion 17 adapted to receive a strap 18, and projecting from the side of this wheel 16 is the grooved projection 19 which has the groove 20 therein. Slidably mounted on the strip 12 is the member 21 which has the upstanding projections 22 and 23, which projections have the notches 24 therein and secured to the member 21, intermediate the projections 22 and 23 is the spring member 25, which projects backwardly and upwardly and again backwardly, which spring is adapted to hold the flyer leg 26 in the notches 24, 70 and the base portion of the flyer which is indicated by the numeral 27 projects into the groove 20. The member 21 has threadably secured therein the bolt 30 by means of which the member 21 may be adjustably secured 75 along the strip 12. Projecting upwardly and forwardly from the table 10 is the strip 31, against which the projection 19 is adapted to lie in normal position and secured on the lower portion of this strip 31 is the pulley 80 32 which is adapted to receive the strap 18, which strap extends downwardly and has the weight 33 secured to its lower end. The other end of the strap 18 projects downwardly in front of the table and is connected 85 to one end of a pedal member 34, the other end of the pedal 34 being pivotally secured to the floor as at 35. The strap 18 is fixedly secured to the wheel 16 by means of the bolt 36 to prevent relative movement between the 90 strap and the wheel 16.

In Figures 2 and 8 the portion 40 is shown which has been worn away by the presser, and the purpose of this invention is to provide means for turning the flyer while material is being welded on the worn portion 40.

In operation, the operator takes a worn

flyer and with the parts in the position shown in Figures 2, 3 and 4, the flyer is inserted into the groove 20 and the hollow leg 26 is inserted in front of the spring 25 and pushed 5 downwardly into the notches 24. In this position the operator starts the welding operation on the portion 40 and by pressing his foot on the pedal 34 the wheel 16 is partially rotated and the projection 19 rotates there- 10 with to the positions shown in dotted lines in Figures 3 and 4, thus causing the leg 26 of the flyer to remain in the notches 24 but to be given approximately from one-half to a three-quarter turn and while the same is 15 thus being turned the welding operation is carried out, and after the weld is cooled, this portion 40 is then passed on to a grinding machine where the portion 40 is ground and a new bearing portion for the presser is pro- 20 vided.

In the drawings and specification, I have set forth a preferred embodiment of my invention, and although specific terms are employed, they are used in a generic and descriptive sense only and not for purposes of limitation, the scope of the invention being set forth in the appended claims.

I claim:

1. In a support for flyers, a table, a holding member adjustably mounted on the table, and being adapted to hold the leg of the flyer to be repaired, a cooperating holding device for said flyer rotatably mounted on the table, and means for rotating the cooperating holding device and the flyer about said leg of the flyer as an axis.

2. Supporting means for flyers for roving frames while the same are being repaired, a table, a strip mounted along the forward 40 edge of the table, a member slidably mounted on the strip, means associated with said member for holding the tube leg of the flyer to be repaired, rotatable cooperating holding means mounted at one end of the strip and 45 adapted to receive the base portion of the flyer and means for imparting rotary movement to the said rotatable means and to the flyer about said leg as an axis.

3. A device for supporting flyers for fly frames while the same are being repaired comprising a table, upwardly projecting notched members slidably mounted on the table, resilient means associated with said notched members, said means being adapted 55 to hold the leg of a flyer to be repaired, a wheel mounted at one end of the table and having a grooved projection extending from one side thereof in which the base portion of the flyer is adapted to fit, means for imparting rotary movement to the wheel, all of 60 said parts being adapted to operate to hold and turn a flyer about said leg as an axis during a welding operation.

4. In a supporting device for welding flyers, a frame work, a member slidably mount-

ed on the frame work and being adapted to resiliently hold one leg of a flyer to be repaired, a rotatable support mounted on the end of the frame work and having a grooved arm into which the base of the flyer 70 is adapted to fit, and means for turning the rotatable support to turn the flyer about said leg as an axis.

5. In a support for flyers while the same are being repaired, a member adapted to 75 hold one leg of the flyer and being adapted to be adjusted on a frame work, a rotatable member mounted on the frame work and having a grooved arm into which groove the base of flyer is adapted to fit, and means for 80 imparting rotation to the rotatable member to impart rotation to the flyer about said leg as an axis.

6. In a support, a frame work, a bar mounted on the frame work, a member slidably mounted on said bar, means associated with said member for resiliently holding a leg of a flyer to be repaired, a rotatable member mounted on the bar, a grooved arm associated with said rotatable member, said groove being adapted to receive the base of 85 the flyer, and means for imparting rotation to the rotatable member and the flyer associated therewith about said leg as an axis.

7. In a device for supporting flyers while 90 the same are being repaired, a frame work, a bar on said frame work, a rotatable member mounted on said bar, a grooved arm associated with said rotatable member, adjustable means mounted on the bar and being 95 adapted to resiliently hold one leg of the flyer to be repaired, and means for imparting rotation to the rotatable member and to the flyer held thereby about said leg as an axis.

8. In a support for holding a forked member while the same is being repaired, a holding member for one leg of the forked member to be repaired, and means for turning the forked member at will about said leg as an 100 axis.

9. In a support for a forked member while the forked member is being repaired, a table, a holding member adjustably mounted on the table, and being adapted to hold a leg 115 of the forked member while the same is being repaired, a cooperating holding device for said forked member rotatably mounted on the table, and means for rotating the co-operating holding device and the forked member 120 about said leg of the forked member as an axis.

10. In a supporting device for repairing forked members having bases, a frame work, a member slidably mounted on the frame work and being adapted to resiliently hold one leg of a forked member to be repaired, a rotatable support mounted on the end of the frame work and having a groove into 125 which the base of the forked member is 130

adapted to fit, and means for turning the rotatable support to turn the forked member about said leg as an axis.

11. In a support for forked members having bases while the same are being repaired, a holding member adapted to hold one leg of the forked member and being adapted to be adjusted on a frame work, a rotatable

member mounted on the frame work and having a groove into which groove the base 10 of the forked member is adapted to fit, and means for imparting rotation to the rotatable member to impart rotation to the forked member about said leg as an axis.

In testimony whereof I affix my signature.

ALBERT M. GUILLET.
